[57] CLAIM

The ornamental design for a bowling glove, substantially as shown.

DESCRIPTION

FIG. 1 is a bottom plan view of a bowling glove showing my new design;

FIG. 2 is a top plan view thereof;

FIG. 3 is a side elevational view thereof as seen from the right-hand side of FIG. 2;

FIG. 4 is a front elevational view thereof as seen from the top of FIG. 2;

FIG. 5 is a side elevational view thereof as seen from the left of FIG. 2; and

FIG. 6 is a rear elevational view thereof as seen from the bottom of FIG. 2.
